UNITED STATES PATENT OFFICE

2,487,167

WINDOW VENTILATOR

Steve Mora, Detroit, Mich., assignor to Inter-City Manufacturing Company, Detroit, Mich., a co-partnership

Application May 22, 1947, Serial No. 749,761

1 Claim. (Cl. 98—97)

1

This invention relates to building construction, and has particular reference to a ventilator suitable for use with a conventional window sash, storm sash, and the like.

An object of the invention is to generally improve devices of this character, and to provide a ventilator which is simple in construction, economical to manufacture, and efficient in operation.

Another object of the invention is the provision of a device of the character indicated, which may be combined with a conventional window sash whereby various degrees of ventilation may be effected without the necessity of moving the window sash.

Another object of the invention is to provide a simplified ventilator which is constructed and arranged so that it may be mounted on any conventional window sash whether the sash be old or new.

The foregoing and other objects and advantages of the invention will become more apparent as the description proceeds, reference being made from time to time to the accompanying drawings, forming part of the within disclosure, in which drawings:

Fig. 1 is an elevational view of the device embodying the invention shown mounted on a conventional window sash.

Fig. 2 is a section taken on the line 2—2 of Fig. 1.

Fig. 3 is a section taken on the line 3—3 of Fig. 1.

Fig. 4 is an enlarged section taken on the line 4—4 of Fig. 1.

Referring now more particularly to the drawings, it will be understood that in the embodiment herein disclosed, the reference character 7 indicates the sill of a conventional window in which is mounted the sash 8 having glass 9. Secured to the inside face of the sash 8 by means of screws 9, or other suitable means, is a face plate 10 which is provided with a peripheral flange 11 which lies in a plane parallel to the plane occupied by the principal area of the face plate 10.

The face plate 10 is slotted, as at 12 and 13, to accommodate the finger grips 14 and 15 formed on the rectangular gate 16. The finger grips 14 and 15 are rotatably secured to the slidale gate 16, as at 15A, Fig. 3. The finger grips 14 and 15 are formed of a flat stock, which is thin enough to be extendable through the slots 12 and 13 so

that they may be inserted through the slots and rotated 180 degrees, after which they serve to prevent the disengagement of the slidale gate 16 from the face plate.

5 The face plate is provided with circular openings 17, 18, and 19 which are adapted to register with corresponding openings 17A, 18A, and 19A formed in the slidale gate 16 and corresponding openings 20 (Fig. 2) formed in the sash 8 when 10 the parts are in the position shown by the solid lines in Fig. 1. When the parts are in the position shown by the dotted lines in Fig. 1, the openings 17, 17A, 18, 18A, 19, and 19A are then out of register, and the openings 17, 18, and 19, and 15 the corresponding opening 20 in the sash 8 are in effect closed so that no air may go through the sash 8.

With this device it is obvious that various degrees of ventilation may be effected through the sash 8.

20 Having described my invention, what I claim and desire to secure by Letters Patent is:

An article of manufacture comprising a face plate having a peripheral flange defining a rectangular area, a flat plate slidale in said rectangular area, said face plate and said flat plate having registerable openings therein, a longitudinal slot in said face plate, and a flat finger grip having a neck portion of substantially the same width as said slot and having a thickness less than 25 the width of said longitudinal slot peened to said gate and arranged to pivot with respect thereto, said finger grip being adapted to extend through said longitudinal slot when turned in one position.

35 STEVE MORA.
